The ornamental design for an electric mixer as shown and described.

DESCRIPTION

1. Electric mixer

1.1 : Perspective

1.2 : Front

1.3 : Rear view

1.4 : Right side view

1.5 : Left side view

1.6 : Top

1.7 : Bottom

The broken line shown is for the purpose of illustrating portions of the electric mixer and forms no part of the claimed design; Use: the design is incorporated in a mixer,

(Continued)

in particular an electric mixer; Innovative points: the innovation points of the design are in the particular shape of the base of the mixer and of the knob. Another innovative portion is in the jug, which is shaped and coupled to the base of the mixer so as to protrude directly from the top surface of the base as illustrated in the drawings; Figure that shows the design most sufficiently: perspective view (Fig. 1.1).

1 Claim, 7 Drawing Sheets
